(57) **CLAIM**

The ornamental design for a snare drum strainer, as shown and described.

DESCRIPTION

FIG. 1 is a perspective view of the snare drum strainer.

FIG. 2 is a front view thereof.

FIG. 3 is a left-side view thereof.

FIG. 4 is a rear view thereof.

FIG. 5 is a right-side view thereof.

FIG. 6 is a bottom view thereof.

FIG. 7 is a top view thereof.

FIG. 8 is a front view of the snare drum strainer with a handle portion thereof rotated and a carrier portion thereof lowered; and,

FIG. 9 is a front view of the snare drum strainer as mounted onto a snare drum, shown in broken lines.

The broken lines shown in the Figures represent unclaimed subject matter and form no part of the claimed design.
